(57) **CLAIM**

The ornamental design for a hand-held electric tool for slicing and grinding as shown and described.

DESCRIPTION

FIG. 1 is a front elevational view of a first embodiment of a hand-held electric tool for slicing and grinding showing our new design;

FIG. 2 is a rear elevational view thereof;

FIG. 3 is a left side view thereof;

FIG. 4 is a right side view thereof;

FIG. 5 is a top plan view thereof; and

FIG. 6 is a bottom plan view thereof.

FIG. 7 is a perspective view thereof;

FIG. 8 is another perspective view thereof;

FIG. 9 is a front elevational view of a second embodiment of the hand-held electric tool for slicing and grinding showing our new design;

FIG. 10 is a rear elevational view thereof;

FIG. 11 is a left side view thereof;

FIG. 12 is a right side view thereof;

FIG. 13 is a top plan view thereof; and

FIG. 14 is a bottom plan view thereof.

FIG. 15 is a perspective view thereof; and,

FIG. 16 is another perspective view thereof.

The broken lines showing portions of the article form no part of the claimed design.

1 Claim, 8 Drawing Sheets
